UNITED STATES PATENT OFFICE.

FREDERICK COATES, OF ROCHESTER, NEW YORK.

PAPER BOTTLE.

1,218,984.

Specification of Letters Patent.

Patented Mar. 13, 1917.

Application filed June 23, 1916. Serial No. 105,511.

To all whom it may concern:

Be it known that I, FREDERICK COATES, a citizen of the United States, residing at Rochester, in the county of Monroe and 5 State of New York, have invented a new and Improved Paper Bottle, of which the following is a specification.

This invention, while relating in general to bottles and like liquid containers made of 10 paper, has more especial reference to paper bottles in which milk is delivered from the dairy to the consumer, and embodies certain novel features of construction as will herein-after be fully described in the specification 15 and defined in the claims.

The main object of the invention is to provide a substitute for the glass milk bottle of the type in common use that is of substantially the same conformation, strong in 20 construction and inexpensive to manufacture.

A further object is to form the wall or body from a tube of preferably waxed paper, such tube having equally spaced and gradually deepening channels, extending from substantially its center to one end, which give strength to the bottle and its upper portion a conical formation.

A still further object is to strengthen and 30 add finish to the bottle by encircling its open end with a reinforcing member comprising a combined cap-seat and ferrule slotted to engage in interlocking relation with the corrugations of the fluted wall.

The accompanying drawings illustrating 35 a milk bottle made in accordance with my invention are as follows:

Figure 1 is a top plan view of the bottle before the reinforcing member has been attached; Fig. 2, a part side elevation and part vertical central sectional view of the completed bottle; Fig. 3, a top plan view of the reinforcing member comprising the combined cap-seat and ferrule; and Fig. 4, 45 a vertical central sectional view of such member.

Similar reference characters refer to similar parts throughout the several views.

The numeral 1 indicates the wall or body 50 of the bottle comprising a tube formed, preferably, of waxed paper wound upon a mandrel under heated pressure. This tube is placed in a die press and fluted for substantially half its length, as indicated, the 55 channels 2 thus formed being equally spaced

circumferentially and gradually deepening from their inner to their outer ends.

Encircling the open end of the bottle is a reinforcing member 3 formed of any suitable composition material, preferably non-metallic, and comprises a ferrule 4 from which extends upwardly an annular flange 5. The ferrule 4 has formed therein equally spaced tapering slots 6, alternating with similarly tapering lateral projections 7 65 adapted to engage with a perfect fit the fluted wall. When the member 3 is placed on the bottle, the fluted end of the wall extends slightly above the top of the ferrule portion 4 and is thereafter turned over to 70 form the flange 8 which firmly holds such member in place, longitudinally, and against removal, while downward displacement thereof is prevented because of the gradually increasing diameter of the wall 1. The 75 ferrule 4 of the member 3 prevents the fluted end of the bottle from spreading, thus holding it in conical formation, and the tops of the projections 7 with the flange 8 turned thereover form within the flange 80 portion 5 a seat for the usual paper sealing-cap, indicated in dotted lines, Fig. 2, by the numeral 9.

The bottom 10 of the bottle is set part way 85 into the lower end of the tubular wall 1 and has a downwardly extending annular flange 11 turned upon itself to inclose the end of the tube in the usual manner.

What I claim is:

1. As a new article of manufacture, a 90 bottle of the character described comprising a bottom, a wall formed of paper and having a longitudinally fluted portion, and a ferrule slotted to form interlocking engagement with said fluted wall portion at the 95 open end of the bottle.

2. As a new article of manufacture, a 100 bottle of the character described comprising a bottom, a wall formed of paper and having a conical portion in which are formed equally spaced longitudinally extending channels gradually deepening toward their outer ends, and a ferrule slotted to form interlocking engagement with said fluted wall portion at the open end of the 105 bottle.

3. As a new article of manufacture, a 110 bottle of the character described comprising a bottom, a wall formed from a paper tube and having a conical portion in which

are formed equally spaced longitudinally extending channels gradually deepening toward their outer ends, a ferrule slotted to form interlocking engagement with said fluted wall portion at the open end of the bottle, and engaging means bent from the said wall portion to hold the ferrule against removal.

4. As a new article of manufacture, a bottle of the character described comprising a bottom, a wall formed from a paper tube and having a conical portion in which are formed equally spaced longitudinally extending channels gradually deepening 15 toward their outer ends, a ferrule slotted to form interlocking engagement with said fluted wall portion at the open end of the bottle, and a flange turned from the said wall portion to hold the ferrule against removal.

5. As a new article of manufacture, a bottle of the character described comprising a bottom, a wall formed from a paper tube and having a conical portion in which are formed equally spaced longitudinally extending channels gradually deepening toward their outer ends, and a reinforcing member encircling the open end of the bottle comprising a seat for a sealing-cap and 25 a ferrule which is slotted to form interlocking engagement with the said fluted wall portion.

6. As a new article of manufacture, a

bottle of the character described comprising a bottom, a wall formed from a paper tube and having a conical portion in which are formed equally spaced longitudinally extending channels gradually deepening toward their outer ends, a reinforcing member 35 encircling the open end of the bottle comprising a seat for a sealing-cap and a ferrule which is slotted to form interlocking engagement with the said fluted wall portion, and a flange bent from the end of the said wall portion to hold said member against removal.

7. As a new article of manufacture, a bottle of the character described comprising a bottom, a wall formed from a paper tube and having a conical portion in which are formed equally spaced longitudinally extending channels gradually deepening 50 toward their outer ends, a reinforcing member slotted to form alternating tapered channels and projections having interlocking engagement with the said fluted wall portion, engaging means bent from the end of the said wall portion to hold the reinforcing member against removal, and an annular flange extending upwardly from 55 said member, the tops of the said projections and the open end of said fluted wall portion forming within the flange a seat for a sealing-cap.

FREDERICK COATES.
